UNITED STATES PATENT OFFICE.

JAMES J. McCARTHY, OF CHICAGO, ILLINOIS.

CAR.

No. 851,022.

Specification of Letters Patent.

Patented April 23, 1907.

Application filed December 29, 1905. Serial No. 293,780.

To all whom it may concern:

Be it known that I, JAMES J. McCARTHY, a citizen of the United States, residing at Chicago, in the county of Cook and State of Illinois,

have invented certain new and useful Improvements in Cars, of which the following is a specification, reference being had to the accompanying drawings.

My invention relates to cars, and has particularly to do with the frame of the car and with the construction of the roof.

It has for its object to provide an improved metallic frame arranged so that the siding may be secured thereto by nailing; also, to provide improved metallic carline as well as improved means for securing the roof of the car in position. I accomplish this object as hereinafter described, and as illustrated in the drawings.

What I regard as new is set forth in the claims.

In the accompanying drawings, Figure 1 is a perspective view illustrating my improvements. Fig. 2 is a vertical section on line 2 2 of Fig. 4. Fig. 3 is a section on line 3 3 of Fig. 2. Fig. 4 is a plan view of the parts shown in Fig. 2. Fig. 5 is a partial vertical section on line 5 5 of Fig. 1. Fig. 6 is a detail illustrating a modification. Fig. 7 is a perspective view illustrating a modified arrangement. Fig. 8 is a partial sectional view on an enlarged scale. Fig. 9 is a transverse section on line 9 9 of Fig. 8. Fig. 10 is a cross-section on line 10 10 of Fig. 7. Fig. 11 is a perspective view of parts of a car, illustrating the construction of the frame. Fig. 12 is a vertical sectional view of one end portion of the car, illustrating the arrangement of the side and end sills. Fig. 13 is a plan view of the construction illustrated in Fig. 12, some parts being in section; and Fig. 14 is a vertical section on line 14 14 of Fig. 12.

Referring to the drawings, 11 12 indicate the side plates of the car, and 13 the usual wooden siding of matched boards. As best shown in Fig. 1, the side plates 11 12 are connected by carlines 14, composed of angle-irons, the flanges of the angle-irons being arranged to extend vertically and laterally, respectively, with the internal angle on the upper side to adapt the carlines to receive filler strips or blocks 15, which are fitted in the carlines and extend transversely of the car parallel with the carlines, their ends abutting against the side plates 12, as shown

in Fig. 1. Said filler blocks or strips are of wood or other equivalent material suitable for receiving the nails by which the roofing-boards 16 are secured in place.

As shown, the carlines are so shaped as to provide the desired slant for the roof; but they may be otherwise shaped, if desired. The intermediate carlines are preferably all alike; but as it is desirable that both end carlines face outward it is necessary to provide a reversed carline 17 at one end of the car, as shown in Fig. 1. The vertical flanges 14^a of the carlines 14 are bent laterally at their ends to form lateral lips 18, as shown in Fig. 1, which have an extended bearing against the side plates, and similarly the lateral flanges 14^b of said carlines are bent twice at right angles, as shown at 19 in Fig. 1, to provide stirrups which extend under the side plates, as shown in Figs. 1 and 2. If desired, the ends of the lateral flanges 14^b may be bent upward between the side plates and the siding, as shown at 20 in Fig. 6, thus providing a more secure connection between said parts. The lips 18 and stirrups 19 are secured to the side and bottom surfaces, respectively, of the side plates by nails or screws or by bolts 21, as shown in Fig. 2, or all of these devices may be employed together. In like manner the end carline 17 is provided with lips 18^a and stirrups 19^a, which serve the same purpose as the lips and stirrups 18 19. The filler strips or blocks 15 fit closely in the carlines, and, as shown in Figs. 1 and 5, their upper and side surfaces are flush with the upper and side edges of the carlines, also with the upper surfaces of the side plates. They are secured to the carlines preferably by nails 23, extending through suitable holes in the carlines and through the filler-strips 15, being clenched, as shown at 24 in Fig. 4.

In the construction shown in Fig. 1 the roofing-boards are illustrated as extending longitudinally of the car and are fitted directly upon the upper edges of the carlines and the filler-strips 18, being nailed to said filler-strips, as illustrated. In the construction shown in Fig. 7 roofing-boards 25 are shown which extend transversely of the car. Where this construction is employed, the carlines and filler-strips are set sufficiently below the upper surface of the side plates 11 12 to accommodate purlins 26, which rest upon the carlines and the filler-blocks and are secured thereto by nails 27. (Shown in dotted lines in Fig. 8.) The roofing-boards are nailed to the

purlins so that they are indirectly secured to the filler strips or blocks. If desired, by using long nails the nails which secure the roofing-boards in place may also be caused to extend into the filler-strips; but usually that is unnecessary. It will be understood that with either construction the roofing-boards are secured to the filler blocks or strips and that my invention, so far as the generic 10 claims are concerned, is not restricted to the specific means shown for accomplishing that end.

The siding 13 is secured to the side plates in the usual way, and at the ends of the car it is secured to the filler blocks or strips carried by the end carlines in substantially the same way that the roofing-boards are secured to the carlines. It is necessary to reverse one of the end carlines, as shown at 17 in the drawings, in order to get the filler-strips on the outside at both ends of the car.

In Figs. 11 to 14 I have illustrated the application of my improvements to the lower as well as the upper portion of the frame of a car. As shown in said figures, the side sills 28 29 are made of angle-iron and provided with filler-blocks 30 31, respectively. The end sills 32 33 are also angle-iron and are provided with filler-blocks 34 35, respectively. It will be understood that the two side sills are oppositely disposed, so that the filler-blocks are on the outside, and that in like manner the end sills are oppositely disposed for the same purpose, thus placing the filler-blocks so as to be adjacent to the siding, which is nailed thereto in the ordinary way. The filler-blocks may be secured in place by nails or bolts or in any other suitable manner. As shown in said figures, the ends of the vertical flanges of the end sills are bent at right angles, as shown at 36 in Figs. 11 and 13, and are secured to the vertical flanges of the side sills. The horizontal flanges of the end sills extend under the horizontal flanges of the side sills, as shown at 37 in Figs. 12 and 14, and are riveted or otherwise secured thereto. By this construction the side and end sills are made to overlap, so that the parts of the frame are held together very securely, making a very strong and rigid construction. The end sills are secured together by longitudinal pieces 38, which are also angle-iron, and are provided with filler-blocks 39 to which the flooring-boards 40 are secured.

I wish it to be understood that my invention is not restricted to specific details of the constructions shown and described, except in so far as they are particularly claimed, but includes generically the subject-matter of the broader claims.

That which I claim as my invention, and desire to secure by Letters Patent, is—

1. In a car, the combination of side plates and a metallic carline extending across the car and connected with said side plates, said

carline consisting of an angle-iron, the flanges whereof extend vertically and laterally respectively, the internal angle being on the upper side, the ends of said vertical flange being bent laterally so as to abut against said side plates and being secured thereto, and a wooden filler-strip fitted in the angle of the carline, the ends of said strip abutting against said side plates.

2. In a car, the combination of side plates, a metallic carline extending across the car and connected with said side plates, a filler-strip resting upon said carline and arranged parallel therewith, the ends of said filler-strip abutting against said side plates, wooden purlins extending longitudinally of the car and secured to said filler-strips, and a roof secured to said purlins.

3. In a car, the combination of side plates, and metallic carlines extending across the car, the ends of said carlines being bent downward and extended under the side plates to form supports therefor.

4. In a car, the combination of side plates, a metallic carline extending across the car, said carline consisting of an angle-iron, the flanges whereof extend vertically and laterally respectively, the internal angle being on the upper side, the ends of said vertical flange being bent laterally to engage said side plates and being secured thereto, and a filler-strip carried by said carline and arranged parallel therewith, the ends of said filler-strip abutting against said side plates.

5. In a car, the combination of side plates, a metallic carline extending across the car, said carline consisting of an angle-iron, the flanges whereof extend vertically and laterally respectively, the end portions of said vertical flange being bent laterally and secured to said side plates, and the end portions of said lateral flange being bent downward and extended under the side plates.

6. In a car, the combination of side plates, and a metallic carline extending across the car, said carline consisting of an angle-iron, the flanges whereof extend vertically and laterally, respectively, the internal angle being on the upper side, the lateral flange of said carline being bent downward and extended under the side plates.

7. In a car, the combination of side plates, and a metallic carline extending across the car, said carline consisting of an angle-iron, the flanges whereof extend vertically and laterally, respectively, the internal angle being on the upper side, the end portions of the vertical flange being bent laterally and secured to the side plates, the lateral flange of said carline being bent downward and extended under the side plates.

8. In a car, the combination of side plates, a metallic carline extending across the car, said carline consisting of an angle-iron, the flanges whereof extend vertically and later-

ally, respectively, the internal angle being on the upper side, the end portions of the vertical flange being bent laterally and secured to the side plates, the lateral flange of 5 said carline being bent downward and extended under the side plates, and a filler-strip carried by the carline.

9. In a car, the combination of side plates, metallic carlines extending across the car at 10 the ends thereof and connected with said side plates, said carlines being composed of angle-iron, the internal angle of each of said carlines being on the outside, filler-strips carried by said carlines, and end boards secured 15 to said filler-strips.

10. In a car, the combination of side and end sills composed of angle-iron, the flanges of said angle-irons being arranged vertically and horizontally respectively, the internal 20 angle thereof being on the outside, the end portions of the vertical flanges of certain of said sills being bent at right angles so as to abut against the vertical flanges of the adjoining sill and being secured thereto, filler-blocks fitted in said sills, and siding secured 25 to said filler-blocks.

11. In a car, the combination of side and end sills composed of angle-iron, the flanges of said sills being arranged vertically and 30 horizontally respectively, the end portions

of certain of said sills being bent at right angles and secured to the vertical flanges of the adjoining sill, the end portions of the horizontal flanges of certain of said sills being extended under and secured to the horizontal flanges of the adjoining sills, and filler-blocks fitted in said sills. 35

12. In a car, the combination of side and end sills composed of angle-iron, the flanges of said angle-irons being arranged vertically 40 and horizontally respectively, the internal angle thereof being on the outside, the end portions of the horizontal flanges of certain of said sills being extended under and secured to the horizontal flanges of the adjoining 45 sills, and filler-blocks fitted in said sills.

13. In a car, the combination of side and end sills composed of angle-iron, the flanges of said angle-irons being arranged vertically and horizontally respectively, the internal 50 angle thereof being on the outside, the end portions of the horizontal flanges of certain of said sills being extended under and secured to the horizontal flanges of the adjoining sills, filler-blocks fitted in said sills, and 55 siding secured to said filler-blocks.
